UNITED STATES PATENT OFFICE.

AUTHUR R. HAVENER, OF WAYLAND, MASSACHUSETTS, ASSIGNOR TO JUDSON L. THOMSON MANUFACTURING CO., OF WALTHAM, MASSACHUSETTS, A CORPORATION OF MASSACHUSETTS.

RIVETING MACHINE.

Application filed February 10, 1925. Serial No. 8,124.

This invention relates to a machine for punching and riveting sheet material, and particularly to a mechanism for supporting the work while the latter is being subjected to the punching and riveting operations.

In the riveting machine upon which my invention is employed there are separate punching and rivet setting instrumentalities, together with a mechanism for alternately moving each of said instrumentalities into the same operative position relatively to the sheet material comprising the work, the latter first having a hole punched therein by the punching instrumentalities 10 which are then withdrawn, and with the work remaining in its initial position the rivet setting instrumentalities are moved into alignment with the hole that has been punched, after which a rivet is inserted therethrough and subsequently clinched.

In a machine of this type it is very essential that the work shall be supported in such a manner that it will not be moved during the interval that the punching instrumentalities are being withdrawn therefrom and the rivet setting instrumentalities are being fed into alignment with the hole that has been punched, for if said hole is not in alignment with the rivet holding and setting instrumentalities, the rivet will not enter the hole provided therefore but will be forced through said work in an objectionable manner and at an undesirable location, thereby ruining the work.

It is an object, therefore, of this invention to provide a mechanism for normally supporting the work which consists of thin sheet material a slight distance above a die which forms a portion of the punching instrumentalities, said mechanism being so arranged that it will permit said work to yield downwardly and rest upon said die during the punching operation, said work again returning to its normal position above and out of contact with said die after the punching and stripping instrumentalities have been withdrawn therefrom, thereby enabling said die to be moved beneath said work and in a direction parallel to the under surface thereof, and the anvil forming a part of the riveting instrumentalities moved into alignment with the hole that has been formed in said work without moving the latter.

The invention also contemplates a construction of work support that will permit the work to be fed thereon between the successive riveting operations without interference from the anvil.

The invention consists of a riveting machine as set forth in the following specification, and particularly as pointed out in the claims thereof.

The machine of this invention is an improvement over a similar machine for which I have also filed an application for Letters Patent, Serial No. 706,103 filed April 12, 1924 to which reference may be had for a more complete description.

Referring to the drawings:

Figure 1 is a left hand side elevation of a riveting machine, a work support embodying my invention being illustrated in connection therewith.

Fig. 2 is a horizontal section taken on the line 2-2 of Fig. 1.

Fig. 3 is a front elevation of a portion of the punching and rivet setting mechanisms.

Fig. 4 is a plan view of the work support.

Fig. 5 is a vertical section taken on the line 5-5 of Fig. 4 illustrating the work support in its normal position; the die and anvil of the punching and rivet setting instrumentalities being illustrated associated therewith.

Fig. 6 is a vertical section taken on the line 6-6 of Fig. 5.

Fig. 7 is a vertical section similar to Fig. 6 illustrating the position that the work support assumes during the punching operation.

Like numerals refer to like parts throughout the several views of the drawings.

In the drawings, 10 is the frame of the machine and 11 is a hopper in which the rivets employed by the machine are held in a mass and from which they are fed in a well known manner to the rivet setting instrumentalities. Mounted upon the frame 10 is an auxiliary frame 12, the latter being rigidly fastened in any suitable manner to a vertical shaft 13 which is mounted to rock in bearings 14 and 15 formed integral with the frame 10. The auxiliary frame 12 embodies therein a head portion 16 located at the forward end thereof in which a rivet

carrier slide 17 and a rivet carrier 18 of well known construction are mounted to slide in a vertical direction. Also mounted in the head 16 at one side of the rivet carrier 5 slide 17, see Fig. 3, is a punch slide 19 at the lower end of which is a punch holder 20 carrying a punch 21. Mounted in the head 12 at the rear of the rivet carrier slide 17 is a stripper slide 22, the latter carrying a 10 stripper 23 at its lower end. Located upon the opposite side of the rivet carrier slide 17 from that upon which the punch slide 19 is located is a driver slide 24, the latter carrying a driver 25 at its lower end, see 15 Fig. 3.

The rivet carrier slide 17, punch slide 19, stripper slide 22 and driver slide 24 are grouped closely together within the head 16, all being adapted to be moved vertically 20 within said head by mechanisms hereinafter to be described, all of said slides being held in said head by a bearing plate 26 which is secured to the front of said head.

A rocking movement is imparted to the 25 auxiliary frame 12 and shaft 13 by a lever 27 pivoted at 28 to the frame 10, one end of said lever 27 being operatively connected by a link 29 with said frame 12, while the other end of said lever has a cam roll 30 journaled thereon, the latter projecting into a suitable groove formed in the periphery of a cam 31 fast to a shaft 32, the latter being driven in any suitable manner from a main driving shaft 33.

35 The work, as for example, sheet material A, which is to be operated upon is supported upon a work support hereinafter to be described, which is secured at the outer end of an arm 34 formed integral with the frame 40 10. Mounted in the arm 34 is a slide 35 which is slidable in a horizontal plane between ways 36 formed in said arm. The slide 35 is securely held in the arm 34 by a plate 37 which is detachably secured to the 45 upper surface of said arm. The slide 35 carries at its forward end a die 38 and an anvil 39 of well known construction, and a passage 40 is provided in said slide for the purpose of carrying off the small particles 50 of metal that are punched from the sheet material A.

The sheet material A which constitutes 55 the work is supported, during the punching and riveting operations, upon a work support 41, the latter being pivoted at 42 to a bracket 43 in turn mounted upon the plate 37. The work support 41 is slotted at its 60 forward end at 44, thereby forming fingers 45 upon which the material A rests, a flat spring clamp 46 being provided for the purpose of holding the sheet material upon the upper edge of said fingers. The spring clamp 46 is secured to the work support 41 in a manner to rock in unison therewith and 65 is provided with an opening 47 located

adjacent to the forward end thereof through which portions of the punching and riveting mechanisms may project. The work support 41 is held in the position illustrated in Fig. 5 by a coil spring 48, the latter acting 70 to hold said work support in its normal raised position, which is determined by a stop 49 at the rear end of said work support engaging with an abutment 50 formed upon the bracket 43. When the work support is 75 located in its normal position, the sheet material A will be held at a slight distance above the upper surfaces of the die 38 and anvil 39 as illustrated in Fig. 5.

Stops 51 are provided upon opposite sides 80 of the work support 41 for the purpose of limiting the rearward movement of the work A upon the work support. The stops 51 are adjustably secured in the work support 41 by suitable screws 52.

85 A reciprocatory movement is imparted to the slide 35 in order that the die 38 and anvil 39 may be positioned to co-operate with the punch 21 and driver 25 respectively by mechanism as follows:—Rigidly secured in any 90 suitable manner to the vertical rock shaft 13 is an arm 53, and the latter is operatively connected by a link 54 to a bell crank lever 55 pivotally mounted at 56 upon the frame 10. The bell crank lever 55 is in turn connected by an adjustable connecting rod 57 with a bracket 58 rigidly fastened to the slide 35. It will, therefore, be seen that the mechanism which imparts the swinging movement to the auxiliary frame 12 is 100 utilized to impart a reciprocatory movement to the slide 35.

A vertical reciprocatory movement is imparted to the punch slide 19 by a lever 59 pivoted at 60 upon the frame 10 and the front extremity 61 of said lever 59 is cylindrical in form and projects into a sliding block 62 which is mounted in a member 63 rigidly secured to the upper extremity of the punch slide 19. A rocking movement is imparted to the lever 59 by a cam 64 which is fast to the shaft 32. As the punch slide 19 descends, it carries with it the stripper slide 22, and when the punch 21 engages the work A resting upon the work support 41, said work is forced downwardly carrying with it the work support until the work rests upon the die 38, after which the punch is forced through said work and a hole is formed therein. The punch 21 and stripper 23 then rise, the latter a very slight amount, and after said stripper 23 has been released from the work in a manner hereinafter to be described, the work support 41 and the work thereon will return to their normal positions.

120 The stripper 23 which is forced downwardly by the punch slide 19 during the downward movement of the latter is held in a position to strip the work A from the 130

punch 21 during the upward movement of the latter by a pawl 65 pivoted at 66 to the arm 12 of the frame 10, said pawl engaging a notch 67 provided in the stripper slide 22 and being held in said notch by a spring 68. The pawl 65 is released from the notch 67 during the upward movement of the punch slide 19 by a cam 69 fast to said punch slide, said cam engaging a pin 70 projecting laterally from the pawl 65, thereby allowing said stripper to move upwardly to its normal position.

A vertical reciprocatory movement is imparted to the driver slide 24 by a lever 71 pivoted at 72 upon the frame 10, and the front extremity 73 of said lever 71 is cylindrical in form and projects into a sliding block 74 which is mounted in a member 75 rigidly secured to the upper extremity of the driver slide 24. The lever 71 is rocked by a cam 76 which is fast to the shaft 32. As the driver 25 descends to force a rivet α located in the rivet carrier 18 from the latter and through the opening that has been punched in the work, the work support 41 and work thereon will be forced downwardly as the under side of the rivet head engages the work until said work is deposited upon the upper surface of the anvil 39, after which the rivet is clinched to the material in the usual well known manner. When the driver again rises, the work support and work thereon will again rise and return to their normal positions.

The general operation of the mechanism hereinbefore specifically described is as follows:—The work A which consists of very thin sheet material is placed upon the work support 41 beneath the spring clamp 46, the latter securely holding said work upon the upper edges of the fingers 45 at the forward end of said work support. At this time the work support 41 is located in its raised or normal position in which position it is held by the spring 48, and the work A is located a slight distance above the upper surface of the die 38 and anvil 39.

The punch 21 and stripper 23 next descend and the punch 21 upon engaging the work forces the latter downwardly together with the work support 41, depositing said work upon the upper surface of the die 38, after which said punch continues downwardly, punching the hole in said work. The punch and stripper then move upwardly allowing the work support 41 and work A to return to their normal positions, and if it happens that a slight bur or flange has been formed by the punch 21 around the edge of the hole which might cause the work to be moved upon the work support during a movement of the slide 35 beneath said work, the possibility of such interference with the work is eliminated by the removal of the work from engagement with the die 38.

The rivet setting instrumentalities are now moved into alignment with the hole that has been formed in the work A, the auxiliary frame 12 being rocked to position the rivet carrier 18 and driver 25 above said hole, 70 and the slide 35 being moved beneath said work to align the anvil 39 with said rivet carrier and driver, after which a rivet α located in said carrier is forced therefrom and inserted in said hole, said rivet subsequently 75 being clinched to said work in the usual well known manner. The driver 25 then rises and the work support 41 and work A which have been forced downwardly during the riveting operation again move upwardly to 80 their normal positions, leaving sufficient space between the clinched end of the rivet α and the upper surface of the anvil 39 to permit an operative to manually feed said work A into position to receive the next rivet 85 without there being any interference between the anvil 39 and the previously inserted rivet. When the work has been correctly positioned to receive another rivet, the sequence of operations previously mentioned is repeated in attaching other rivets until the rear edge of the work A engages the stops 90 51 which determine the position of the last rivet to be inserted in said work.

I claim:

1. A machine for punching and riveting sheet material comprising, in combination, punching instrumentalities embodying therein a punch and die, rivet setting instrumentalities embodying therein a driver and anvil, a work support including a pair of fingers normally positioned to support sheet material at a distance above said die and anvil, means to impart a rectilinear reciprocating movement to said die and anvil between said fingers, said work support being adapted to be forced downwardly to bring said sheet material into contact with said die and anvil by said punch and driver respectively during the downward movement of each, and means to return said work support and sheet material to their normal positions after each downward movement. •

2. A machine for punching and riveting sheet material comprising, in combination, a yielding work support including a pair of fingers, a slide mounted beneath said work support and projecting upwardly between said fingers and embodying therein a die and anvil, a punch, a driver, means to alternately move said slide to position said die and anvil in alignment with said punch and driven respectively, means to move said punch into co-operative relation with said die to punch a hole in said sheet material, and means to subsequently move said driver to force a rivet through said hole and clinch the same in said material, said work support being adapted to be forced downwardly to bring said sheet material into contact with said die 130

4
and anvil by said punch and driver respectively during the downward movement of each.

3. A machine for punching and riveting sheet material comprising, in combination, a main frame, an auxiliary frame pivotally mounted upon said main frame, a punch and driver mounted upon said auxiliary frame, a slide mounted upon said main frame and embodying therein a die and anvil, a work support pivotally mounted upon said main frame and adapted to normally support sheet material at a distance above said die and anvil, means to clamp said sheet material upon said work support, means to alternately move said punch and driver into the

same operative position relatively to said sheet material and to move said slide to position said die and anvil to co-operate with said punch and driver respectively, said work support being adapted to be forced downwardly to bring said sheet material into contact with said die and anvil by said punch and driver respectively during the downward movement of each, and means to return 25 said work support and sheet material to their normal positions after each downward movement.

In testimony whereof I have hereunto set my hand.

ARTHUR R. HAVENER.
